UNITED STATES PATENT OFFICE.

GEORGE BAYLEY WILLIAMS, OF TEXARKANA, TEXAS.

AUTOMATIC ELECTRIC ALARM.

SPECIFICATION forming part of Letters Patent No. 552,803, dated January 7, 1896.

Application filed April 8, 1895. Serial No. 544,962. (No model.)

To all whom it may concern:

Be it known that I, GEORGE BAYLEY WILLIAMS, of Texarkana, in the county of Bowie and State of Texas, have invented a new and 5 Improved Automatic Electric Alarm, of which the following is a full, clear, and exact description.

This invention relates to automatic electric alarms, and more especially to that class of 10 such alarms which are adapted for employment in connection with automatic dry-pipe sprinkler systems for protection against fire, the alarm when so employed being arranged to operate in such a way as to give warning 15 when the air-pressure in the pipes of the sprinkler system falls below a predetermined point, whether such fall be occasioned by the opening of the pipes for the discharge of water in the case of fire, or whether it be occasioned by leakage of the pipes; and the object of the invention is, in part, to provide an 20 alarm of this character adapted to indicate, first, the fall of the air-pressure in the pipes of the system, and in case this warning be unnoticed to continue in operation, and, finally, 25 to give warning that the water has entered the pipes of the system, and in part to provide certain improvements in the arrangement of the circuit-wires for an electric alarm of this general character.

The invention consists in certain novel features of construction and arrangements of parts whereby the automatic electric alarm constructed in accordance with my invention 35 presents certain advantages for use over other similar devices heretofore employed, all as will be hereinafter fully set forth.

The novel features of the invention will be carefully defined in the claims.

Reference is to be had to the accompanying 40 drawings, forming a part of this specification, in which similar figures of reference indicate corresponding parts in all the views.

Figure 1 is a vertical axial section taken 45 through the circuit-closing device of the alarm in the plane indicated by line $x-x$ in Fig. 2. Fig. 2 is a plan view of the said circuit-closing device. Fig. 3 is a perspective detail view showing the form of the spring employed for 50 holding the contacts of the circuit-closing device normally out of engagement. Figs. 4 and 5 are side elevations showing modified forms

of the circuit-closing device, to be hereinafter referred to; and Fig. 6 is a somewhat diagrammatic view showing the arrangement of the 55 independent main and local circuit-wires, both adapted to be closed by one circuit-closer or contact-valve similar to the valve shown in Fig. 1, but provided with two sets of contacts.

In the drawings, 1 represents the body or 60 casing of the circuit-closing device provided on its under side with a screw-threaded tubular nipple 2, adapted for attachment to the pipes of the sprinkler system, as will be hereinafter set forth, the upper part of said casing 1 being open and screw-threaded interiorly 65 to receive the cap or cover 3, having a central tubular boss 4 extending from its upper side and aligned with the opening of the nipple 2.

The casing 1 is provided below its screw-threaded upper portion with a raised annular seat 5 concentric with and opposite to the lower depending annular lip 6 of the cap or cover 3, and the said seat 5 and lip 6 are adapted to clamp and hold between them 70 when the cap or cover 3 is secured in place a diaphragm 7, having a central perforation through which extends the screw-threaded stem 8 of a head 9 having a convex upper face 75 adapted to conform to the curvature of the 80 diaphragm 7 when the same is bowed or bent upward under the pressure in the pipes, as indicated in Fig. 1.

The upper end of the boss 4 of the cap or cover 3 is interiorly screw-threaded to receive 85 a screw-threaded tubular plug 11, in which is arranged to play a stem 12, whereon is coiled below the plug 11 a spring 13, the lower end of which is arranged to bear on the upper portion of an enlargement or head 14 formed on 90 the lower end of the stem 12 inside the chamber formed between the casing 1 and its cap or cover 3, and said head or enlargement 14 is provided with a convex under surface 15 corresponding with and opposite to the concave surface 10 of the head 9, being provided at its center with an interiorly-threaded perforation 16, wherein screws the stem 8 of the head 9 in such a manner that the diaphragm 7 is securely clamped at its central part between the opposite convex surfaces 10 and 15 of the respective heads 9 and 14, as shown in Fig. 1.

At its upper end the stem 12 is screw-

threaded, as indicated at 17, to receive a nut 18 having a hexagonal enlargement 19 at its upper part arranged to rest normally on the end of a contact-finger 20, pivoted at 21 between the forks of a forked bearing-piece 22, secured to the upper end of an insulated support 23 secured on the cap or cover 3. The bearing-piece 22 is formed with a screw-threaded shank (seen in dotted lines in Figs. 1 and 2) extending through the support 23 and provided with a nut 24, adapted to serve as a binding-screw to secure thereto the circuit-wire, and also adapted to hold the bearing-block in place on the support 23. The nut 18 or its flange or enlargement 20 may, if desired, be of insulating material.

In order to maintain the contact-finger 20 normally distended in a horizontal plane, as seen in Fig. 1, I employ a spring 25 of sheet metal. (Seen in detail in Fig. 3.) This spring 25 is adapted to lie on the upper flat face of the bearing-piece 22, being provided at its rear end with depending fingers 26 and at its opposite sides adapted to be secured between the end of the piece 22 and the support 23 on opposite sides of the shank of the said bearing-piece, whereby, when the nut 24 is tightened on said shank, the fingers 26 will be securely clamped between the support 23 and bearing-piece 22, in order to secure the spring 25 in place. At its forward end the spring 25 is similarly provided with a central depending finger 27, adapted to extend between the forks of the bearing-piece 22 and bear elastically against the rear face of the contact-finger 20.

Below the bearing-piece 22 a contact-piece 28 is secured to the insulated support 23, being provided with a screw-threaded shank 40 similar to the shank of the said bearing-piece, extending through the support and adapted to receive a nut 29, whereby the contact-piece 28 is securely clamped to the support 23 similarly to the bearing-piece 22, the end of the circuit-wire being similarly secured. At its extremity the contact-piece 28 is provided with a depending lug or lip 30, having a beveled upper surface 31, and the contact-piece 28 is arranged relatively to the bearing-piece 22 and its contact-finger 20, so that when the finger 20 falls, as indicated in dotted lines in Fig. 1, its end will contact with said beveled surface 31 on the contact-piece 28, so as to close the circuit, as will be hereinafter described.

55 In applying the alarm shown in Figs. 1, 4 and 5 in practice I employ either local circuits and alarms only, or I connect the contact-valves or circuit-closing devices of the various independent branches of the sprinkler system in series with one main circuit. In Fig. 6 is shown the sprinkler-pipe 32 provided with a connection 33, to the end of which is coupled the circuit-closer or contact-valve constructed as above set forth, the nipple 2 of the casing 65 1 being screwed into the open head of the connection 33, as will be readily understood.

As a six or eight inch pipe leading up from

the water-mains can only furnish water at an adequate pressure to a limited number of sprinkler-heads with one-half inch openings 70 when all have been opened in the case of a fire, it is necessary to have an independent connection of water-mains to furnish the adequate pressure to sprinkler-heads in excess of what can be supplied with a pressure from 75 one water-pipe, and so on, until there are sufficient connections with water-mains to furnish adequate pressure to all sprinkler-heads in buildings or shops of any character. The pipes normally filled with compressed air to 80 hold back the water-pressure in one water-pipe leading to water-mains are not connected with the pipes containing compressed air which hold back the water-pressure in another water-pipe leading to water-mains, but each 85 rises from the main valve, air-pipes, air-gage and sprinkler-heads. Each such independent branch of the sprinkler system must also have its own contact-valve and alarm whether with a local circuit and generator or in a main circuit 90 wired in multiple with contact-valves or circuit-closers in similar independent branches of the sprinkler system.

When the circuit-closing device is employed, as shown in Fig. 6, it is provided with 95 an auxiliary insulated support 23^a similar to the support 23 above described and provided at its upper end with a bearing-piece 22^a, contact-finger 20^a and contact-piece 28^a, similar to the corresponding parts 22, 20 and 28 of the 100 circuit-closing devices shown in Fig. 1. The several circuit-closing devices (of which but one is shown in Fig. 6) are connected in multiple by means of wires 38 with the main alarm-circuit consisting of the circuit-wires 35 and 105 including a generator 36 and a bell 37, said bell being located at any suitable point in the building—as at the office, for example. The several circuit-closing devices are also each included in a local circuit consisting of circuit-wires 34, and each of said local circuits includes a generator 39 and a bell 40.

The operation is as follows: When the air-pressure in the pipe falls below the predetermined point, the spring 13, acting on the head 115 of the stem 12, presses down the same so that the contact-finger 20 is forced down to the position seen in dotted lines in Fig. 1 into contact with the contact-piece 28 so as to close the circuit between the contact-finger 20 and contact-piece 28, whereby the local circuit including the battery 39 and bell 40, and also the main circuit including the battery 36 and bell 37, are closed, and the alarm sounded at two points. By this arrangement of the main 120 and local circuits it is evident that should either circuit be impaired so as to be inoperative the alarm of the other circuit will still be sounded so as to give warning of the fall of the air-pressure in the pipes of the system. The tension of the spring 13 may be adjusted by 125 turning the screw-plug 11 so as to regulate and vary the point at which the signal will be given, and this point will be by pref-

erence sufficiently high to cause the signal to be sounded some little time before the main valve will open to admit water to the air-pipes in case of ordinary leakage, so that in such 5 case the admission of water to the air-pipes may be prevented.

In Fig. 4 I have shown a modified arrangement of the circuit-closer, wherein the nut 18 is inverted and has its hexagon 19 at its 10 base. The contact-piece 28 is also inverted in this form of the device, and the spring 25 being omitted the contact-finger 20 rests directly on the hexagon 19, and when the nut 18 moves down at the fall of air-pressure in 15 the pipes the said contact-finger 20 falls by gravity into engagement with the contact-piece 28, so as to close the circuit and sound the alarm. In this form of contact-valve the contact is automatically broken, as well as 20 automatically made, this being adapted for giving a leakage-alarm only.

If desired, a similar construction of circuit-closing device may be employed to indicate the rise of pressure above a predetermined point, and I have shown in Fig. 5 such 25 a device. This construction is similar to that shown in Fig. 4, excepting that the contact-piece 28 is arranged above the bearing-piece 22, and the finger 20 is adapted to be moved 30 upward into engagement therewith, to close the circuit and sound the alarm when the pressure under the diaphragm rises. This form of contact-valve is intended for causing an alarm when a column of water accumulates on the valve from condensation in the 35 air-pipes, or when water passes from the water-mains into the air-pipes. For the former purpose the contact-valve should be attached to the lowest point of the air-pipes.

40 From the above it is evident that my invention is susceptible of some modification in the construction and arrangement of the several parts, and for this reason I do not wish to be understood as limiting myself to 45 the precise form herein shown.

Having thus described my invention, I claim as new and desire to secure by Letters Patent—

1. In an electric alarm, the combination of 50 a casing, a diaphragm therein adapted to be moved in one direction by the increase of pressure in the casing on one side thereof, a stem connected to the diaphragm, a cap for the casing, a spring connected to said cap, and adapted to exert a regulated yielding pressure on the diaphragm, a contact piece, 55 and a contact finger actuated by said stem and adapted to be moved into contact with said contact piece, when the diaphragm is moved in one direction and adapted to stand in the position in which it is moved when the diaphragm is moved in the other direction, substantially as set forth.

2. In an electric alarm, the combination of 60 a casing, a diaphragm therein adapted to be moved in one direction by the increase of

pressure in the casing, on one side thereof, a cap for the casing, a stem movably mounted on the cap, heads at the lower end of said stem, said heads being secured together on 70 opposite sides of said diaphragm and having adjacent convex faces bearing against the same, a spring connected to the stem, and two contact points one of which is connected to and adapted to be moved by the stem into 75 and out of contact with the other contact point, substantially as set forth.

3. In an electric alarm, the combination of a casing, a diaphragm therein, a stem connected to the diaphragm, means for applying 80 a regulated spring pressure on one side of the diaphragm and a fluid pressure on the other side thereof, a contact piece, a contact finger connected to the stem and adapted to be moved into contact with the contact piece 85 by the same, and a spring independent of the spring employed for actuating the diaphragm connected to the finger and adapted to hold the same normally out of contact with the contact piece, substantially as set forth. 90

4. In an electric alarm, the combination of a casing, a diaphragm therein, a stem connected to the diaphragm, means for applying a regulated spring pressure to one side of the diaphragm and a fluid pressure to the other 95 side thereof, a contact piece, a bearing piece, an insulated support therefor, a clamp screw for holding said bearing piece to its support, a contact finger pivoted to the bearing piece and connected to the stem, and a spring having at one end projections held between the bearing piece and its support on opposite sides of the clamp screw, and having its other end arranged to bear on the contact finger and hold the same normally out of contact with 100 the contact piece, substantially as set forth. 105

5. In an alarm, the combination of a main circuit including a generator and an alarm, a series of local circuits each including a generator and an alarm, and a circuit closer comprising a diaphragm arranged to be operated by fluid pressure and four contacts, two of 110 which are movable and are actuated by the diaphragm, said movable contacts being connected in different circuits and being each 115 arranged when the diaphragm is moved in one direction to simultaneously close its particular local circuit and the main circuit, and when the diaphragm is moved in the other direction to stand in its closed position, whereby 120 said circuits are maintained closed, substantially as set forth.

6. In an electric alarm, the combination of a casing, a diaphragm therein, means for applying a fluid pressure to one side and a regulated yielding pressure to the other side of the diaphragm, a stem for said diaphragm having an enlargement, a contact piece forming one terminal of an electric circuit, and a pivoted contact finger connected to said enlargement and forming the other terminal of the 125 said circuit, said pivoted finger being 130

adapted to be moved into and out of contact with said contact piece, substantially as set forth.

7. In an electric alarm, the combination of 5 a casing, a diaphragm therein, means for applying a fluid pressure to one side and a regulated yielding pressure to the other side of said diaphragm, a screw threaded stem for the diaphragm, a nut screwing on said stem, 10 a contact point forming one terminal of an electric circuit, a pivoted contact finger connected to said nut and forming the other terminal of said circuit, said pivoted contact finger being adapted to be moved into and out 15 of contact with said contact piece, substantially as set forth.

8. In an electric alarm, the combination of a casing, a diaphragm therein, means for applying a fluid pressure to one side and a regulated yielding pressure to the other side of 20 said diaphragm, a stem for said diaphragm

a contact piece forming one terminal of an electric circuit, a contact finger connected to said stem and forming the other terminal of said circuit and a spring, independent of the 25 spring employed for actuating the diaphragm, connected to and arranged to actuate said contact finger, substantially as set forth.

9. The combination, of a support, a bearing piece, a clamp screw for holding the bearing piece to the support, two contact fingers, one of which is pivoted to the bearing piece, and a spring having one end clamped between the bearing piece and the support and having its other end connected to and adapted to actuate 35 said pivoted contact finger, substantially as set forth.

GEORGE BAYLEY WILLIAMS.
